UNITED STATES PATENT OFFICE.

JOHN NATZI WHITEHOUSE, OF NEW YORK, N. Y., ASSIGNOR TO WM. DEMUTH & CO., OF NEW YORK, N. Y., A CORPORATION OF NEW YORK.

TOBACCO-PIPE.

1,308,612.

Specification of Letters Patent.

Patented July 1, 1919.

Application filed September 13, 1918. Serial No. 253,908.

To all whom it may concern:

Be it known that I, JOHN NATZI WHITEHOUSE, a citizen of the United States, residing at New York, in the county of New York and State of New York, have invented 5 certain new and useful Improvements in Tobacco-Pipes, of which the following is a specification.

My invention relates to tobacco pipes and 10 particularly to pipes having removable tubes which form the smoke channels and serve as collecting means for the tobacco juice and saliva.

An object of my invention is the provision 15 of a pipe of the above described character wherein the removable tube is so constructed that, irrespective of its position in the pipe, it will form a free and unrestricted conduit for the passage of the smoke.

20 I will describe one form of pipe and tube embodying my invention and will then point out the novel features thereof in claims.

In the accompanying drawing, Figure 1 is a view showing in vertical section one 25 form of pipe embodying my invention having applied thereto one form of removable tube embodying my invention;

Fig. 2 is a section taken on the line 2—2 of Fig. 1; and

30 Fig. 3 is a perspective view of the removable tube.

Similar reference characters refer to similar parts in each of the several views.

Referring to the drawings, A designates 35 the bowl of a smoking pipe, B the stem and C the mouthpiece. As shown in Fig. 1, the inner wall of the bowl A is formed with a circular recess 12 formed in the forward side wall of the bowl A, such recess being 40 of a diameter corresponding to the diameter of the bore 11 of the pipe stem. The diameter of the bore 11 is uniform throughout its length with the exception of its right hand end which is enlarged to receive the mouthpiece C. The bore of the mouthpiece 45 C indicated at 13, freely accommodates one end of a tube T.

The tube T is formed of any suitable material such as aluminum, and adjacent both 50 ends it is formed at diametrically opposite points with elongated openings 14, as shown in Fig. 2.

In practice, the tube T is inserted into the stem B, and when pushed home the forward end of the tube rests within the recess 55 12 and the openings 14 are centrally dis-

posed above the bottom of the bowl, and slightly spaced from the same. The mouthpiece C is now inserted into the stem B, the bore 13 of the mouthpiece receiving the tube 60 T. The tube T need not be cut to length with any great exactness, because when it is in position in the pipe it extends only a short distance into the inner end of the mouthpiece C, which as shown may be bored 65 out through its whole length.

As in similar forms of pipes, the tube T is designed to serve the functions of a smoke and residue collecting channel, and is removable to permit the cleaning of the same. 70 Heretofore, tubes of this character have been so constructed that it has been necessary to carefully insert the tube in the pipe in a predetermined position so that the opening at the inner end of the tube will be presented 75 upwardly to communicate with the bowl and to thus convey the smoke therefrom. With the present invention, the tube T may be carelessly inserted in any position, either end to, and still secure the proper communication between the bowl and tube. This is due first, to the disposition of the openings 14, as it will be manifest that, irrespective 80 of the position of the tube, either opening or a portion thereof is presented upwardly 85 within the bowl; and secondly to the fact that these openings are provided at each end of the tube, in each case at the same distance from the end, so that either end 90 may be inserted through the stem B. Furthermore the distance from recess 12, through bore 11 and bore 13, is greater than the length of tube T, so that the tube may be of varying lengths, provided only that it must project sufficiently from bore 11 so 95 that it may be readily removed.

Although I have herein shown and described only one form of pipe and tube embodying my invention it is to be understood that various changes and modifications may 100 be made without departing from the spirit and scope of the appended claims.

I claim:

1. A smoking pipe comprising a bowl portion, a stem, a mouthpiece removably fitted in the stem, a tube removably fitted in the stem and projecting therefrom partways into the mouthpiece and formed with openings to effect communication between the bowl of the pipe and the tube in any position to 110 which the tube may be turned in the stem, said bowl portion being recessed above the

- bottom wall thereof to receive the forward end of said tube, and the mouthpiece being bored to freely accommodate the opposite end of the tube.
- 5 2. A smoking pipe comprising a bowl portion, a stem, a mouthpiece removably fitted in the stem, a tube removably fitted in the stem and projecting therefrom partways into the mouthpiece and formed at each 10 end with openings to effect communication between the bowl of the pipe and the tube in any position to which the tube may be turned in the stem, said bowl portion being recessed above the bottom wall thereof to receive the forward end of said tube, and 15 the mouthpiece being bored to freely accommodate the opposite end of the tube.

In testimony whereof I affix my signature.

JOHN NATZI WHITEHOUSE.
